CLAIM

The ornamental design for a connection shield, as shown and described.

DESCRIPTION

FIG. 1 is a left perspective view of our new design;

FIG. 2 is a left view thereof;

FIG. 3 is a bottom view, the top view being a mirror image thereof;

FIG. 4 is a rear view thereof;

FIG. 5 is a front view thereof;

FIG. 6 is a left view thereof including a clasp mechanism depicted in dashed lines; and,

FIG. 7 is a left perspective view thereof including a clasp mechanism depicted in dashed lines.

The elements depicted in dashed lines form no part of the ornamental design.
